UNITED STATES PATENT OFFICE.

ROBERT N. COX, OF WAUKEGAN, ILLINOIS.

MILK-BOTTLE-CAP REMOVER.

1,419,823.

Specification of Letters Patent. Patented June 13, 1922.

Application filed July 11, 1921. Serial No. 483,859.

To all whom it may concern:

Be it known that I, ROBERT N. Cox, a citizen of the United States, residing at Waukegan, in the county of Lake and State 5 of Illinois, have invented certain new and useful Improvements in Milk-Bottle-Cap Removers; and I do hereby declare the following to be a full, clear, and exact description of the invention, such as will enable 10 others skilled in the art to which it appertains to make and use the same.

Milk bottles and like wide mouthed containers sealed by paper closures frequently splash their contents when removing the 15 closure, this being due to the flexible nature of the closure which yields suddenly when attempting to thrust a fork or other pointed instrument therein preliminary to removal of the closure in the ordinary way.

20 This invention provides the paper cap or closure with a pull piece in the nature of a strip which extends diametrically across the under side of the cap, with its ends folded thereover and secured thereto, one of the 25 ends being loose to be gripped between the thumb and finger of the hand when drawn upon in the act of opening the bottle.

Other objects and advantages will be apparent and suggest themselves as the nature 30 of the invention is understood.

While the drawing illustrates an embodiment of the invention it is to be understood that in adapting the same to meet different conditions and requirements, various changes 35 in the form, proportion and minor details of construction may be resorted to without departing from the nature of the invention.

Referring to the accompanying drawing forming a part of the specification,

40 Figure 1 is a top plan view of a paper closure provided with a pull piece embodying the invention,

Figure 2 is a view of the same inverted.

45 Figure 3 is a section on the line $x-x$ of Figure 1,

Figure 4 is a view similar to Figure 1 of a modified view,

Figure 5 is a top plan view of a further modification,

50 Figure 6 is a section on the line $y-y$ of Figure 5,

Figure 7 is a still further modification,

Figure 8 is a section on the line $z-z$ of Figure 7.

55 Corresponding and like parts are referred

to in the following description and designated in the several views of the drawing by like reference characters.

The numeral 1 designates a paper cap such as generally provided for sealing milk bottles and likewise mouth containers. In accordance with the present invention a strip 2 of suitable material extends diametrically across the under side of the cap 1 and its end portions are folded about the edges of the cap and against the top thereof. The 60 folded ends are made secure in any manner either by a suitable adhesive or other determinate way. The strip 2 may be of any material such as paper or textile and is 65 treated to render the same moisture proof. The folded ends of the strip 2 are indicated at 3 and 4, the end portion 4 being longer than the folded end 3. The terminal portion of the folded end 4 is left loose, as indicated 70 at 5, to provide a convenient grip when removing the closure. In the preferable arrangement the loose end 5 is in contact with the top of the cap 1 so as to facilitate the 75 stacking of a number of the caps either for storage or when in position in the capping machine. In the event of paraffin being used to render the strip 2 moisture proof and as stiffening means therefor it may also serve as means for securing the folded 80 ends 3 and 4 to the top or outer side of the cap. The intermediate portion of the strip 85 2 may be loose or secured as desired.

The loose end 5 may be reinforced, as indicated at 6 in Figure 4, by a metal binding, 90 or by means of a metal tip 7, as indicated in the remaining views. A depression 8 is provided to receive the reinforced end of the strip to admit of its coming flush with the 95 top of the cap.

In the modification shown in Figures 7 and 8 the folded ends 3 and 4 of the strips 2 are secured between the plies or layers of the cap and the upper ply or layer has its central portion cut away to provide the depression 8 for the reception of the reinforced end 7 of the strip 2.

To open a milk bottle sealed by a cap embodying the invention it is necessary only to lift the loose terminal portion 5 and grip the same between the thumb and finger of the hand and exert a pull thereon. This results in detaching or loosening the folded end 4 and enables the pull to be applied at the edge of the cap which yields readily 110

and comes away from the bottle without any tendency to splash the contents thereof which is objectionable when removing paper closures in the accustomed way by the use 5 of a fork or like pointed instrument.

Having thus described the invention, what I claim is:—

1. A paper cap and an opening strip of substantially uniform width throughout its 10 length having its intermediate portion extending across the under side of the cap, and having its end portion projecting to unequal distances and folded to engage opposite edges of the cap and secured thereto, the 15 shorter end being attached throughout its extent and the longer end having its terminal portion loose to provide a grip which is spaced from the shorter end.
2. A paper cap having an opening strip 20 applied to the under side thereof, and having the end portions of the strip projecting and folded to engage opposite edges of the cap and secured thereto, one of the folded ends having its terminal portion loose and 25 reinforced, the cap having a depression in

its top to receive the reinforced end of the strip.

3. A paper cap having a recess opening through its upper side and an opening strip applied to the under side thereof and having the end portions of the strip projecting and folded to engage opposite edges of the cap and secured thereto, one of the folded ends having its terminal portion loose and reinforced and located in said recess. 30

4. A paper cap comprising layers, the top layer having its central portion cut away, and an opening strip extending along the underside of the cap and having its ends 40 projecting and folded about the edge of the lower layer and secured between the layers thereof, the terminal portion of one of the folded ends lying in the cut away portion of the upper layer of the cap.

In testimony whereof I affix my signature 45 in presence of two witnesses.

ROBERT N. COX.
